UNITED STATES PATENT OFFICE

HERBERT J. LEIGHTON, OF SYRACUSE, NEW YORK, ASSIGNOR TO BROWN-LIPE GEAR COMPANY, OF SYRACUSE, NEW YORK, A CORPORATION OF NEW YORK

STARTER FOR INTERNAL-COMBUSTION ENGINES

Application filed June 8, 1928. Serial No. 283,924.

This invention has for its object a starter for internal combustion engines which is particularly simple and compact in construction and highly efficient and durable in use and in which the starter pinion is automatically shifted out of mesh with the engine gear when the engine is started.

It also has for its object, a starter in which the starting pinion moves laterally at an angle to its axis into and out of mesh with the engine gear instead of axially and a relative arrangement of the starter gear and pinion and the engine gear by which the driving action of the starter gear moves the pinion planetarily into mesh with the engine gear and the driving action of the engine gear shifts or crowds the starting pinion planetarily out of mesh therewith.

The invention consists in the novel features and in the combinations and constructions hereinafter set forth and claimed.

In describing this invention, reference is had to the accompanying drawings in which like characters designate corresponding parts in all the views.

Figure 1 is a side elevation of an engine starter embodying my invention, the contiguous portion of the electric motor being also shown, the parts being shown in their position assumed when the engine is being started.

Figure 2 is an elevation similar to Figure 1, parts being omitted, the parts being shown as in their normal position.

Figure 3 is a fragmentary view of parts seen in Figure 2 showing the latch in latching position.

Figure 4 is a plan view of parts seen in Figures 1 and 2.

Figure 5 is a sectional view on line 5—5, Figure 1, the contiguous portion of the engine gear being shown.

Figure 6 is a longitudinal sectional view through the starter.

This engine starter comprises generally a pinion normally out of mesh with the engine gear and shiftable into and out of mesh therewith and tending to shift automatically into mesh with the engine gear, the pinion and the gear being so relatively arranged that the driving action of the gear tends to shift

the pinion out of mesh therewith, an operating member holding the pinion in its normal position and shiftable into a position to permit the pinion to shift into mesh with the engine gear and means movable into a position to hold the pinion out of mesh with the gear when it has been moved out of mesh by the driving action of the engine gear and the operating member is in its operated position, said means being controlled in its operation by the operating member and arranged to be reset by the operating member when said member is returned to its normal position.

The pinion is arranged to move in a direction at an angle to its axis into and out of mesh with the engine gear.

The starter comprises generally, a frame 1 designed to be mounted upon the casing or frame 2 of an electric motor, a shaft 3 suitably journaled in the frame and designed to be coupled to the motor shaft 4 when the frame 1 is mounted on the motor frame 2. As here illustrated, the abutting ends of the shafts 3, 4 are formed with a complementary interfitting radially extending tongue 5 and groove 6.

The starter further includes a gear 7 mounted on the shaft 3, a pinion 8 meshing with the gear 7 and movable planetarily about the gear 7 into and out of mesh with the engine gear 9, Figure 5, and being normally out of engagement therewith.

In the illustrated embodiment of my invention, the pinion 8 is supported by a carrier 10 mounted to swing about the axis of the gear 7, the carrier being shown as bifurcated and having hubs mounted upon bushings 11, Figure 6, which bushings are arranged in the bearings for the shaft 3, the bifurcations being interposed between the side faces of the starter gear 7 and the ends of the bearings for the shaft 3. These bifurcations have laterally extending arms which are connected by a yoke piece 12. The arms which carry the yoke piece 12 are arranged at a right angle to the main body of the carrier which supports the axle 13 of the pinion 8. The gear 7 and pinion 8 are here shown as arranged with their axes in a plane tangent to the pitch

circle of the engine gear 9 when the pinion is in mesh with the engine gear so that the starter gear 7 meshes with the pinion 8 in alined radii of the gear 7 and pinion 8 which are arranged at an oblique angle to alined radii of the pinion 8 and engine gear 9 meeting where the pinion 7 and gear 9 mesh. Thus, while the starter gear 7 is driving in the direction of rotation as indicated by the arrow A, Figure 5, it tends to hold the pinion 8 in mesh with the engine gear 9 due to the planetary action of the pinion 8 about the gear 7, but when the engine is started and the engine gear 9 driving, the driving action tends to shift or crowd the pinion 8 out of mesh therewith. This is so whether the engine actually starts or is acting under a flywheel momentum in case it does not start. Thus, the pinion moves out of mesh with the engine gear regardless of whether or not the operator holds the operating member depressed or operated.

The carrier 10 is preferably provided with means tending to move it to carry the pinion 8 into mesh with the engine gear 9, this means being here shown as a spring 14 anchored at 15 to the frame 1 and thrusting at its other end against the yoke piece 12. The spring effects the shifting before the planetary action fully develops.

16 is the operating member, this tending to normally hold the pinion 8 out of mesh with the engine gear 9 and coacting with the carrier 10 for this purpose. The member 16 is shown as a slide rod suitably guided for this purpose. The member 16 is shown as a slide rod suitably guided in the frame and held in its normal holding position by a spring 17. It is actuated in any suitable manner against the holding and returning action of the spring by an operator-operated member, lever or push button not shown, through a lever 18 pivoted at 19 to the starter frame 1 and connected at 20 to the operating member 16. The operating member also carries a switch contact 21 which moves into engagement with the contact 22 on the motor to close the electric circuit through the motor when said member 16 is operated. This feature forms no part of this invention and it is merely necessary to bear in mind that when the operating member 16 is actuated against its spring 17 to permit the pinion 8 to move into mesh with the engine gear 9, the switch contact 21 comes in contact with the motor contact 22 to close the circuit through the motor so that the motor will operate to drive the armature shaft 4 and the starter shaft 3.

The operating member 16 normally coacts with a laterally extending arm 23 on the carrier 10, this arm projecting from the yoke piece 12. The operating member in this embodiment extending under said arm to prevent the action of the carrier by the spring 14 and the operating member is provided with

a slot or recess 24 arranged to come into alignment with the arm 23 to permit the arm 23 to move or drop thereinto under the action of the spring 14 or by the planetary effect before referred to when the arm 23 moves into the recess 24. The pinion 8 moves into mesh with the engine gear 9 and subsequently the contact 21 comes in contact with the motor switch contact 22.

After the engine has been started, the driving effect of the engine gear 9 moves the pinion 8 out of mesh therewith and hence, rocks the arm 23 upwardly out of the recess 24 and if the operator still holds the member 16 in its operated position, the pinion 8 idles.

In order to hold the pinion 8 out of mesh with the engine gear 9 after it is so thrown out of mesh therewith and while the operating member or slide 16 returns to its normal position, means as a latch is provided for holding the pinion 8 out of mesh with the engine gear 9 until the operator releases the operating member 16 so that it can return under its spring 17 to its normal position. This holding means also coacts with the arm 23 and is here shown as a spring pressed latch 25 pivoted at 26 between its ends to the operating member 16 and having a spring 27 connected thereto tending to move it into operative position. The engaging end 28 of the latch partly closes the recess 24 which is of greater width than the arm 23 and approximately twice the width thereof and said engaging end also extends above the holding surface of the operating member 16 so as to encounter during the shifting of the member 16, a side face of the arm 23 at an angle to the side engaging the member 16.

As here shown, the operating member is provided with a laterally extending part or shoulder 29 arranged to engage a suitable notch 30 in the latch. The latch is arranged at one side of the member 16 and laps one side thereof. It is mounted on the outside of the frame 1 which frame is formed with a hole 31 through which the arm 23 extends. The hole 31 is usually provided in a suitable cover plate 32 detachably secured to the frame as by cap screws 33 and the latch is located on the outside of the plate, its pivot 26 extending through a slot 26a in the plate.

In operation, the parts are in their position shown in Figure 1 and during the shifting of the operating member 16 to the left, the end 28 of the latch 25 is partly closing the recess 24 and engages the side face of the arm 23 during such movement of the operating member and is held from further movement under the influence of its spring 27 as the operating member continues to move toward its operated position or to the left. When the operating member has moved to its extreme operated position, the recess 24 is brought into full alinement with the arm 23 and which drops or is moved under the in-

fluence of the spring 14 or the planetary action, into the recess 24. At this time, the pinion 8 is in mesh with the engine gear 9 and the switch contacts 21, 22 are engaged so that the motor is operating to turn the starter gear 7 and actuate the pinion 8 and engine gear 9.

When the engine is started, the driving action of the engine gear 9 shifts or crowds the pinion 8 planetarily relatively to the gear 7 out of mesh with the engine gear and hence swings the carrier 10 to its normal position or slightly beyond its normal position, thereby carrying the arm 23 out of the recess 24, and far enough out of the recess to clear the end 28 of the latch 25. When it does so clear the end 28 of the latch 25, the latch spring 27 reacts to pull the end 28 under the arm 23 thus holding the pinion out of mesh with the engine gear 9.

When the operator releases the operating member 16, the spring 17 returns said member to its normal position as seen in Figure 2 and the shoulder or part 29 thereof resets the latch 25 in its normal position. This part 29 owing to the shape of the notch 30 also prevents overthrow of the latch 25 as seen in Figure 2, or in other words, holds the latch in such position that its end 28 must engage the side face of the arm 23. If the operator releases the member 16 before the engine is started, then the fly wheel momentum of the engine gear 9 will momentarily cause a driving effect which will shift the arm 23 out of the recess 24 and permit the latch 25 to enter under said arm and hold it in its normal position until the operating member 16 is free to return to its normal position.

Owing to the lateral or planetary movement of the starting pinion 8 into mesh with the engine gear, breaking off of gear teeth is avoided as if the gears do not come directly into mesh, a very small initial turning movement of the pinion 8 alines the teeth thereof with the spaces between the teeth of the engine gear, and owing to the relative arrangement of the starting pinion and engine gear, it is thrown out of mesh with the engine gear as soon as the engine starts and the operator can not hold the pinion in mesh with the engine gear after the engine starts. Owing to the latch 25, the pinion is locked out of mesh with the engine gear as soon as the engine gear begins to drive.

55 What I claim is:

1. An engine starter comprising a gear associated with the engine, a starter pinion shiftable into and out of mesh with said gear and normally out of mesh therewith and arranged relatively to the gear to be shifted out of mesh therewith by the driving action of the engine gear faster than the pinion, a carrier for the pinion, support means for the carrier about which said carrier is movable to carry the pinion into mesh with the

gear, and an operating member comprising a slide, the carrier having a portion for engaging the slide whereby the slide holds the carrier in its normal position, the slide having a slot movable into alignment with said portion of the carrier when the operating member is moved to its operative position thereby permitting the carrier to shift the pinion into mesh with the gear.

2. An engine starter comprising a gear associated with the engine, a starter pinion shiftable into and out of mesh with said gear and normally out of mesh therewith and arranged relatively to the gear to be shifted out of mesh therewith by the driving action of the engine gear faster than the pinion, a movable carrier for the pinion movable automatically to carry the pinion into mesh with the gear, and an operating member normally coacting with the carrier to hold it in its normal position and provided with a passage movable into alignment with the coacting portion of the carrier when said member is shifted and thereby permitting the carrier to move the pinion into mesh with the gear, a latch normally held out of operative position by the operating member and by the carrier when the pinion is in mesh with the gear and having means for moving it into position to coact with the carrier and hold the same in its normal position when the pinion has been moved to its normal position by the driving action of the engine gear and the operating member is in its operated position.

3. An engine starter comprising a gear associated with the engine, a starter pinion shiftable into and out of mesh with said gear and being normally out of mesh therewith and arranged relatively to the gear to be shifted out of mesh therewith by the driving action of the engine gear faster than the pinion, a movable carrier for the pinion movable automatically to carry the pinion into mesh with the gear, and an operating member normally coacting with the carrier to hold it in its normal position and provided with a passage movable into alignment with the coacting portion of the carrier when said member is shifted and thereby permitting the carrier to move the pinion into mesh with the gear, a latch normally held out of operative position by the operating member and by the carrier when the pinion is in mesh with the gear and means for moving the latch into position to coact with the carrier and hold the same in its position assumed when the pinion has been returned to its normal position by the driving action of the engine gear and the operating member is held in its operated position, the operating member having means to reset the latch when said member is moved to its normal position.

4. An engine starter comprising a gear associated with the engine, a starter pinion

shiftable into and out of mesh with said gear and normally out of mesh therewith and being arranged relatively to the gear to be shifted out of mesh therewith by the driving action of the engine gear faster than the pinion, a carrier being movable automatically to carry the pinion into mesh with the gear, the carrier having an arm projecting therefrom, an operating member having a portion normally arranged to coact with one side of said arm and hold the carrier in its normal position and a recess arranged to receive said arm and permit the shifting movement of the carrier when said member is shifted to its operated position, a spring actuated latch arranged to engage said arm and hold the carrier in its normal position and being normally out of engagement with the arm, the latch being also arranged to engage another side of said arm at an angle to the former side during the movement of the latch by its spring when said member is being operated, and held by the arm from moving into latching position, and the latch being movable into latching position by the movement of the arm out of the recess by the driving action of the gear on the pinion.

5. An engine starter comprising a gear associated with the engine, a starter pinion shiftable into and out of mesh with said gear and being normally out of mesh therewith and arranged relatively to the gear to be shifted out of mesh with said gear by the driving action of the gear faster than the pinion, a carrier for the pinion having means tending to move it to carry the pinion into mesh with the gear, the carrier having a projecting arm, an operating member having a portion normally engaged with the said arm to hold the carrier in its normal position and a recess for receiving said arm when said member is operated, the recess being of greater width than the arm, a spring pressed latch normally partly obstructing said recess, the arm projecting into the path of said latch, a stop movable with the operating member for normally holding the latch from movement by its spring, the stop being movable out of engagement with the latch when the latch engages a side of the face of said arm and the latch being movable under said arm toward the slot when the pinion is moved out of mesh with the gear by the driving action, said stop acting to reset the latch when the operating member returns to its normal position.

6. An engine starter comprising a gear associated with the engine, a starting gear, a starter pinion meshing with the starting gear and normally out of mesh with the engine gear and movable in a direction at an angle to its axis into and out of mesh with the engine gear, a carrier for the pinion mounted to rock about the axis of the starting gear and having a laterally extending arm, the car-

rier having means tending to move it to carry the pinion into mesh with the engine gear, and an operating member normally arranged to come in alignment with said arm, the pinion being arranged relatively to the engine gear to be moved out of mesh therewith by the driving action of the engine gear.

7. An engine starter comprising a gear associated with the engine, a starting gear, a starter pinion meshing with the starting gear and normally out of mesh with the engine gear and movable in a direction at an angle to its axis into and out of mesh with the engine gear, a carrier for the pinion mounted to rock about the axis of the starting gear and having a laterally extending arm, the carrier having means tending to shift to carry the pinion into mesh with the engine gear, an operating member normally arranged in the path of said arm and having a recess arranged to come into alignment with said arm, the pinion being arranged relatively to the engine gear to be moved out of mesh therewith by the driving action of the engine gear, a spring pressed latch normally arranged to partly close the recess to the entrance of said arm and said arm being normally arranged in the path of the latch whereby the latch is held from movement during the operation of the operating member and is free to move into position to close the recess when the arm is thrown out of the recess by the driving action of the driving gear on the pinion and the carrier.

8. An engine starter comprising a gear associated with the engine, a starting gear, a starter pinion meshing with the starting gear and normally out of mesh with the engine gear and movable in a direction at an angle to its axis into and out of mesh with the engine gear, a carrier for the pinion mounted to rock about the axis of the starting gear and having a laterally extending arm and tending to move to carry the pinion into mesh with the engine gear, an operating member normally arranged in the path of said arm and having a recess arranged to come into alignment with said arm, a spring pressed latch normally arranged to partly close the recess to the entrance of said arm and said arm being normally arranged in the path of the latch whereby the latch is held from movement during the operation of the operating member and is free to move into position to close the recess when the arm is thrown out of the recess by the driving action of the driving gear on the pinion and the carrier, the operating member and the latch having coacting means whereby the latch is reset during the return movement of the operating member.

9. An engine starter comprising a gear associated with the engine, a starter gear, a pinion meshing with the starter gear and normally out of mesh with the engine gear, a

carrier for the pinion mounted to move about the axis of the starter gear and to be shifted by the planetary action of the starter gear on the pinion to carry the pinion into mesh with the engine gear and to be shifted by the driving action of the engine gear planetarily out of mesh with the engine gear, an operating member normally holding the carrier from movement and shiftable into position to permit planetary movement of the carrier by the starter gear and a latch cooperating with the carrier and held out of operative position thereby when the pinion is in mesh with the engine gear and movable into latching engagement with the carrier to hold it in its normal position when the pinion has been moved out of mesh with the engine gear by the driving action of the engine gear, the operating member having means cooperating with the latch to return and hold it in its normal position when the operating member returns to its normal position.

10. An engine starter comprising a gear associated with the engine, a starter pinion shiftable into and out of mesh with said gear and normally out of mesh therewith and arranged relatively with the gear to be shifted out of mesh therewith by the driving action of the engine gear faster than the pinion, a carrier for the pinion movable automatically to carry the pinion into mesh with the gear, an operating member normally coacting with the carrier to hold it in its normal position and provided with a passage movable into alignment with the coacting portion of the carrier when said member is shifted and thereby permitting the carrier to move the pinion into mesh with the gear, a latch carried by and movable with the operating member normally held out of latching position by the carrier when the pinion is in mesh with the gear and means for moving the latch relatively to the operating member to coact with the carrier and hold the carrier in position assumed when the pinion has been returned to its normal position by the driving action of the engine gear and the operating member is in its operated position, the operating member having means to reset the latch when said member is moved to its normal position.

11. An engine starter comprising a gear associated with the engine, a starting gear, a starter pinion meshing with the starting gear and normally out of mesh with the engine gear and movable in a direction at an angle to its axis into and out of mesh with the engine gear, a carrier for the pinion mounted to rock about the axis of the starting gear and having a laterally extending arm, the carrier having means tending to shift or carry the pinion into mesh with the engine gear, an operating member normally arranged in the path of said arm and having a recess arranged to come into alignment with said arm, the pinion being arranged relatively to the engine

gear to be moved out of mesh therewith by the driving action of the engine gear, a spring pressed latch pivoted to the operating member and normally arranged to partly close the recess to the entrance of said arm and said arm being normally arranged in the path of the latch whereby the latch is held from movement during the operating of the operating member and is free to move into position to close the recess when the arm is thrown out of the recess by the driving action of the driving gear on the pinion and the carrier.

12. An engine starter comprising a gear associated with the engine, a starter pinion shiftable into and out of mesh with said gear and normally out of mesh therewith and arranged relatively to the gear to be shifted out of mesh therewith by the driving action of the engine gear faster than the pinion, a carrier for the pinion support means for the carrier about which the carrier is movable to carry the pinion into mesh with the gear, an operating member normally coacting with the carrier to hold it in its normal position, the operating member being movable in a direction at an angle to the plane of the shifting movement of the pinion and having means for holding the pinion out of mesh with the gear and means for returning the operating member to its initial position.

13. An engine starter comprising a gear associated with the engine, a starter pinion shiftable into and out of mesh with said gear and normally out of mesh therewith and arranged relatively to the gear to be shifted out of mesh therewith by the driving action of the engine gear faster than the pinion, a carrier for the pinion support means for the carrier about which the carrier is movable to carry the pinion into mesh with the gear, an operating member normally coacting with the carrier to hold it in its normal position, the operating member being movable in a direction at an angle to the plane of the shifting movement of the pinion and having means for holding the pinion out of mesh with the gear and having a transverse passage movable into alignment with the coacting portion of the carrier when the operating member is shifted and thereby permitting the carrier to move the pinion into mesh with the gear and means for returning the operating member to its initial position.

In testimony whereof, I have hereunto signed my name, at Syracuse, in the county of Onondaga and State of New York, this 29th day of May, 1928.

HERBERT J. LEIGHTON.
